ELECTRIC IRONER

Frederick F. Brueckner, Detroit, Mich., assignor
to William R. Wilson

Application August 15, 1935, Serial No. 36,335

11 Claims. (Cl. 38—60)

The invention relates generally to ironing machines and it has particular relation to an electrically operated ironing machine.

One object of the invention is to provide an electrically operated ironing machine of durable and efficient character which may be manufactured with a minimum amount of expense.

Another object of the invention is to provide an improved ironing machine which may be operated and manipulated with a minimum amount of manual effort so as to minimize fatigue on the part of the operator.

Another object of the invention is to provide an improved ironing machine wherein the parts may be readily assembled so as to reduce the cost of manufacture.

Another object of the invention is to provide an improved ironing machine which will at all times iron materials passed therethrough in a substantially uniform manner regardless of general or localized variations in thickness in the material.

Other objects of the invention will become apparent from the following specification taken in conjunction with the drawings and from the claims hereinafter set forth.

For a better understanding of the invention reference may be had to the drawings wherein:

Figure 1 is a front elevational view of an ironing machine constructed according to one form of the invention;

Figs. 1A and 1B respectively are end views of the elements 42 and 53 of Fig. 1;

Fig. 1C is a fragmentary end view taken along the line 1C—C of Fig. 1.

Figure 2 is a cross sectional view on a larger scale taken substantially along the line 2—2 of Figure 1;

Figure 3 is an end view on a larger scale as seen substantially along the line 3—3 of Figure 1;

Figure 4 is a cross sectional view taken substantially along the line 4—4 of Figure 3;

Figure 5 is an end view of the ironing machine as seen from the right end of Figure 1 with certain parts broken away for the purpose of illustrating details more clearly;

Figure 6 is a front elevational view of an ironing machine constructed according to another form of the invention;

Figure 7 is an end elevational view as seen from the right end of Figure 6, with parts broken away so as to illustrate certain details of the construction.

Referring to Figure 1, the main support for the ironer comprises a casting 10 in the form

of a vertical standard which has foot rests 11 adapted to engage the floor. At its inner side and at the lower end thereof, the casting has a hollow portion 12 for receiving a motor 13. The outer end of the motor shaft is connected to a reduction gearing generally indicated at 14 and a short shaft projecting from the latter has a sprocket wheel 15 for driving a chain 16, which in turn extends vertically within the casting to the upper end thereof and where it is trained about an upper sprocket wheel 18. The latter is mounted on the end of a transversely disposed shaft 19 which projects through a tubular shell 20 secured in openings 21 in the casting such as by welding and bearings 23 in the shell rotatably support the shaft. It may be mentioned at this time that the tubular shell 20 provides a support for an ironing roller generally indicated at 24 and that the shaft 19 serves to drive the roller.

Now referring to Figure 4, it will be noted that the shaft 19 projects slightly beyond the end of the shell 20 and that it is secured to what may be called a driving member 26. This member at three circumferentially spaced points has inwardly projecting cylindrical lug members 27 and these are adapted to substantially fit within openings 28 in a disc member 29. The disc member at its outer edge has a flange 30 snugly fitting within a sheet metal drum 31 and which is rigidly secured to the drum, such as by welding or the like, and the inner edge of the disc has a similar flange 32 rotatably mounted on the shell 20. At its opposite end, the drum, as best shown by Figure 1, similarly has a disc 29 for rotatably mounting this end of the drum on the shell. In this figure also it may be noted that a collar 33 is adjustably fastened on the shell 20 and that a substantial space is provided between the collar and the disc 29 for permitting some inward movement of the drum. It should now be apparent that when the shaft 19 is rotating, with the cylindrical lugs 27 disposed within the openings 28 in the outer disc member 29 on the drum, the drum will be driven also. If at any time it is desired to disconnect the drum from the driving member 26, it is only necessary to move the drum to the right until the lugs 27 are disengaged from the openings 28 and the space between the collar 33 and the right end disc 29 will permit this movement of the drum. It will be understood that, in operation, the load on the drum acts radially thereof and not longitudinally, and therefore does not tend to cause disengagement of the drum from the driving member. Manifestly, however, the collar 33 may be shifted

to the left so as to positively prevent disengagement of the drum from the driving member 26.

The drum, as best shown by Figure 4, may be provided with pad material 35 and this may be enclosed within a canvas cover 36. This arrangement, as will be readily understood, provides a canvas covered and relatively soft ironing surface.

It may be said in general that the ironer also includes an electrically heated pad adapted to be moved vertically to and from the ironing roller and the means for supporting this pad and moving it now will be described.

Referring to Figure 1, a tubular, sheet metal member 40 is provided and the right end of this member projects into openings 41 in the casting 10 and is rigidly secured therein by welding or the like. Outwardly of the casting 10, a tubular casting 42 is mounted on the member 40 and for rigidly holding the tubular casting against rotation on the member 40, opposite end portions of the casting have slots 43 bordered by ears 44 that are adapted to be drawn together by means of bolts 45. This arrangement enables very positively clamping the ends of the casting on the tubular member. As best shown by Figure 5, the casting 42 has an arm portion 47 providing at its outer end a seat for a coiled spring 48 and an offset portion 49 adjacent to but at the opposite side of the casting with respect to the arm 47, provides a seat for another of the springs 48. It may be mentioned in connection with the casting that a rib 50 is provided thereon, as shown by Figure 1, which serves as an end closure and that the casting and tubular member 40 to the left of the arm, as seen in this figure, have openings 51, the purpose of which presently will be described.

A shorter casting 53 is similarly clamped on the left end of the tubular member 40 and this casting has an arm and an offset portion similar to the arm 47 and offset portion 49 on the casting 42 for supporting another pair of similarly disposed springs. Accordingly, it should be understood that the two castings provide a support for four springs located respectively at the corners of an elongated rectangle.

Now referring to Figures 2 and 5 together, a shoe casting 60 is provided having a heating element 61 therein, and this casting extends substantially the length of the rotary drum previously described, and is of arcuate shape so as to substantially correspond in contour to that of the drum. Downwardly opening pockets 62 are provided at the corners of this casting for receiving the upper ends of the springs 48 and it follows that the shoe is supported at its four corners by the four springs 48 and that it is constantly urged upwardly into engagement with the drum by the springs.

For moving the shoe downwardly against the action of the springs 48 so as to separate it from the rotary drum, opposite ends of the shoe, as best shown by Figures 1 and 2, are provided with apertured ears 64 that are pivotally connected to short links 65. These links, as shown by Fig. 1, in turn are pivotally connected respectively to arms 66 and 67 which are secured to a shaft 68 passing through the tubular member 40. The arm 67 is connected to the left end of the shaft 68 beyond the end of the tubular member 40, while the arm 66 passes through the previously mentioned slots 51 in the casting 42 and tubular member 40. Bearings 69, at spaced points in the tubular member 40 and particularly at points 75 adjacent to the arms 66 and 67 and adjacent the

right end of the shaft 68, are provided for supporting the shaft within the tubular member.

The right end of the shaft 68 projects beyond the right end of the tubular member 40 and, as best shown in Figure 5, is secured to a downwardly extending arm 71. This arm, in turn, is pivotally connected at its lower end to a link 72 which, in turn, is pivotally connected to an arm 73 pivoted, as indicated at 74, to the casting 10. The link 72 and arm 73 form a toggle, and their pivotally connected ends are also pivotally connected to a downwardly extending operating member 75. It should now be appreciated that by pulling the member 75 downwardly, the toggle is straightened and the arm 71 connected to the shaft 68 is turned in a counter-clockwise direction which, in turn, causes the arms 66 and 67 to be turned similarly. This movement of the arms 66 and 67 causes the shoe to be pulled downwardly against the action of the springs 48 and thus causes the shoe to be separated from the drum.

As shown in Figure 1, the operating member 75 is pivotally connected at its lower end to an arm 77 which in turn is rigidly secured to a shaft 78 rotatably mounted in a tubular member 79 secured in openings in the lower end of the casting 10, similarly to the mounting of the tubular members 20 and 40. Bearings, similar to those already described, are provided in the tubular member 79 for supporting the shaft. The outer end of the tubular member 79 is provided with a foot rest 80 which may have an opening receiving the end of the member and a set screw 81 is employed for holding it in place on the latter. A foot treadle 82 rests on the tubular member 79 and as best shown by Figure 5, the right end of the treadle has legs 83 and 84 which straddle the tubular member and which are adjustably connected by means of a bolt 85. By this arrangement the right end of the treadle is rotatably, but snugly, held on the tubular member 79. The left end of the treadle 82, as shown by Figure 1, has an apertured lug 86 which receives the end of the shaft 78 beyond the end of the tubular member 79 and for locking the lug 86 to the shaft, a pin 87 projects through the shaft and through the lug.

Now it should be understood that foot pressure on the treadle 82 sufficient to turn it will cause the shaft 78 to turn likewise and hence cause the arm 71 to turn. Since the arm 71 is connected to the operating member 75, the latter will be pulled downwardly and the toggle arrangement previously described will function to pull the shoe away from the rotary drum. Reverse movement of the shoe, treadle and interconnected parts, will occur on account of the action of the springs 48 tending to move the shoe upwardly.

When the treadle is completely depressed so as to straighten the toggle, the straightened condition of the latter will hold the shoe in its lower position as it then will be impossible for the springs to break the toggle. In this connection, attention may be directed to the fact that the treadle has a portion at the left side of the shaft 78, as shown by Figure 5, and in order to break the toggle when the treadle is in its depressed position, it is only necessary to push downwardly on the left side of the treadle. Thus, by foot pressure on the treadle, the shoe may be moved downwardly to a locked position and then released for upward movement by the coiled springs.

As shown by Figure 5, particularly, a switch 75

90 may be mounted on the front side of the casting 10 for completing an electrical circuit to the heating element 61 in the shoe 62. An electric circuit to the motor 13 is completed by means of a switch 91, shown in this figure, which is operatively connected by means of a chain or other flexible member 92 to the operating member 15. This switch is normally closed but when the treadle is fully depressed so as to move the shoe 60 away from the rotary drum, the switch is operated to break the circuit to the motor and thereby interrupt its operation and rotation of the drum.

Referring again to Fig. 5, a support for the material to be ironed is provided as indicated at 95 and this support is bolted to a bracket member 96 which in turn projects under the arms 47 on the castings 42 and 53 and is bolted thereto. A closure member 97 is also secured to the brackets 96 as indicated at 98 and this closure member cooperates with the end closure rib 58 and extends under the tubular member 40 and terminates as indicated at 99 adjacent the other side of the shoe at the opposite side of the drum. It may be mentioned also that the outer side of the casting 10 is provided with a cover plate 100 as shown best by Fig. 1 for concealing the working parts within the castings.

In the form of the invention shown by Figs. 6 and 7, the same general arrangement and principle of operation are employed but in this case a second casting 110 is employed at the left end of the machine in addition to the casting at the right end of the machine. The rotary drum and the mounting thereof on the right end casting is substantially the same as previously described, but the motor for driving the drum is smaller and is located at a lower point. It was found that a small motor might be employed while obtaining sufficient power and this enables using a smaller casting and locating the motor and parts related thereto, in a smaller and more compact space. In this construction inasmuch as a left side support is also provided, the provision of a strong tubular supporting member such as the member 40 in Fig. 1 is not necessary for supporting the shoe and in place of this tubular member, angle members 111 and 112 extend between the two vertical supports and are secured at their ends thereto and these angle members provide supports for the coiled springs previously mentioned. Movement of the shoe vertically against the action of the springs 48 is accomplished by the same method but in this case the operating shaft indicated at 113 and which corresponds to the shaft 68 shown in Fig. 1, is journaled in ears 114 and 115 on the castings respectively. An intermediate bracket support 116 may be secured to the angle member 114 for additionally supporting the shaft. Also it may be mentioned that the support 95 for the material in this instance is secured to angle members 120 welded or otherwise secured to the angle member 112.

The upright supports or castings additionally are connected intermediate their upper and lower ends by means of small tubular members 121 and 122 that serve to tie the two castings together rigidly.

The treadle construction is the same as previously described excepting that the element 88 secured on the left end of the tubular member 19 instead of being supported on the floor is supported by an extended portion 122 on the lower end of the casting 110. In this case the foot rest 75 will be provided under the lower end of the

casting. If desired also the left end of the shaft 18 may extend into the casting 110 and into a bearing therein although this is not necessary as the support provided is substantially the same as that shown by Fig. 1 and this is satisfactory.

In general, it may be added that the ironer may be constructed largely from sheet metal and in this connection, the castings and particularly, the upright supporting castings, might instead be stamped and formed from sheet metal.

The invention according to either of its forms is characterized by a simplicity and efficiency in arrangement and the number of the parts employed. An ironing machine constructed according to the invention may be manufactured in a relatively inexpensive manner which permits its sale to a large group which otherwise would not be able to use electrical ironing machines because of the expense. Moreover the ironing machine is highly efficient in its use. A practically uniform ironing pressure is applied to the material passing through the machine regardless of the thickness of the material or any local variations that may occur in the thickness of the material such as when it becomes wrinkled or folded upon itself. Operation of the machine is simple and requires only a manipulation of the foot pedal which is not difficult and not fatiguing because of the relation of the parts in the treadle operating mechanism. The rotary drum may be easily disengaged from the driving shaft merely by moving it lengthwise and this enables the operator to apply a direct ironing pressure to any material between the heating pad and the drum without at the same time causing rotation of the drum. An ironing machine constructed according to this invention also has a pleasing appearance as it is not bulky or cumbersome and a minimum space is required for accommodating it and moreover practically all operating parts are concealed and this naturally enhances the appearance of the machine. Aside from the above, the ironing machine has a rigidity of construction which insures satisfactory operation, as well as durability.

Although more than one form of the invention has been illustrated and described in detail, it will be apparent to those skilled in the art that various modifications may be made without departing from the scope of the appended claims.

What is claimed is:

1. An ironing machine comprising a standard, a rotary member projecting from the standard, means for driving the member, a drum rotatably receiving the member, means for releasably and drivingly connecting the drum and member and enabling engagement or disengagement thereof by moving the drum axially of the member, and means retaining the drum against removal from the member while still permitting such engagement and disengagement.

2. An ironing machine comprising a standard, a tubular and non-rotatable supporting member projecting from the standard, a driven shaft projecting through the member, a drum rotatably mounted on the member, means on the outer end of the shaft and drum for releasably and drivingly connecting the drum to the shaft, said means being of such character that disengagement and engagement of the drum and shaft is effected by axial movement of the drum on the member, and means on the member at the inner end of the drum for permitting limited but sufficient movement of the latter towards the standard to allow such disengagement.

3. An ironing machine comprising a standard, a tubular member secured to the standard and projecting therefrom, a movable ironing member, means supported in said tubular member for moving said ironing member, arms mounted on the tubular member, and resilient means between the arms and ironing member.
4. An ironing machine comprising a standard, a tubular member secured to the standard and projecting therefrom, a movable ironing member extending along the tubular member, a shaft rotatable in the tubular member, means connecting the shaft and ironing member for effecting movement of the latter upon turning the shaft, and resilient means between the tubular member and ironing member for urging the latter in one direction of movement.
5. An ironing machine comprising a standard, a tubular member secured to the standard and projecting therefrom, a movable ironing member extending along the tubular member, a shaft rotatable in the tubular member, a sleeve mounted on the tubular member and having portions providing seats for resilient members, resilient members engaging said seats and the ironing member, and means connecting the shaft and ironing member for effecting movement of the latter upon turning the shaft.
6. An ironing machine comprising a standard, a movable ironing member carried by the standard, a tubular member projecting from the standard and secured thereto, a shaft rotatably mounted in the tubular member, a treadle rotatable on the tubular member, means connecting the treadle to the shaft, and means interconnecting the shaft and ironing member for moving the latter upon moving the treadle.
7. An ironing machine comprising a standard, a movable ironing member carried by the standard, a rock shaft carried by the standard, a treadle connected to the shaft and having portions projecting beyond opposite sides of the shaft, means including a toggle interconnecting the shaft and ironing member for moving the latter, the projecting portions of the treadle serving to enable pressure on one portion to straighten the toggle to lock the ironing member in one position and pressure on the other portion to break the toggle, and resilient means tending to move the ironing member in the toggle breaking direction.
8. An ironing machine comprising a frame structure, a pair of elongated ironing members one of which may be bodily reciprocated to and from the other, spring means for urging said one member towards the other and for applying the ironing pressure, an arm pivoted in the frame structure in such position that the free end of the arm substantially is located midway between the sides of the movable ironing member and is movable generally parallel to the movement of the latter, a link pivotally connected to the free end of the arm and also pivotally connected to the movable ironing member substantially midway between the sides of the latter, and means for moving the arm about its pivot.
9. An ironing machine comprising a frame structure, a pair of elongated ironing members one of which may be bodily reciprocated to and from the other, spring means for urging said one member towards the other and for applying the ironing pressure, an arm pivoted in the frame structure in such position that the free end of the arm substantially is located midway between the sides of the movable ironing member and is movable generally parallel to the movement of the latter, a link pivotally connected to the free end of the arm and also pivotally connected to the movable ironing member substantially midway between the sides of the latter, means for moving the arm about its pivot, and including a foot treadle pivoted in the frame structure, a toggle connected at one end to the frame and at its other end to the pivoted end of the arm, and means connecting the center of the toggle to the treadle.
10. An ironing machine comprising a frame structure, a pair of elongated ironing members one of which is bodily reciprocatory relative to the other, spring means at the four corners of the movable ironing member for urging it toward the other ironing member, a pair of short links each of which is pivotally connected to the movable ironing member adjacent one end thereof and substantially midway between its sides, a turnable shaft mounted in the frame structure and extending along one side of the movable ironing member, arms fixed respectively to opposite ends of the shaft and having their free ends pivotally connected to the free ends of the adjacent link respectively, the arrangement being such that the pull on the movable ironing member is substantially parallel to its movement when the arms are moved to separate the members, and means for turning the shaft to effect movement of the arms.
11. An ironing machine comprising a frame structure, a pair of elongated ironing members one of which is bodily reciprocatory relative to the other, spring means at the four corners of the movable ironing member for urging it toward the other ironing member, a pair of short links each of which is pivotally connected to the movable ironing member adjacent one end thereof and substantially midway between its sides, a turnable shaft mounted in the frame structure and extending along one side of the movable ironing member, arms fixed respectively to opposite ends of the shaft and having their free ends pivotally connected to the free ends of the adjacent link respectively, the arrangement being such that the pull on the movable ironing member is substantially parallel to its movement when the arms are moved to separate the members, and means for turning the shaft to effect movement of the same, and including a toggle for locking the shaft in position with the ironing members separated.
